United States Patent Office

Des. 193,451
Patented Aug. 21, 1962

193,451

FONT OF CHARACTER NUMERALS

Samuel Ralph Parris, Malvern, Pa., assignor to Burroughs Corporation, Detroit, Mich., a corporation of Michigan

Filed Jan. 19, 1961, Ser. No. 63,617

Term of patent 14 years

(Cl. D64—12)

The FIGURE on the drawing is a face view of a font of character numerals showing my new design.

I claim:

The ornamental design for a font of character numerals, substantially as shown.
